UNITED STATES PATENT OFFICE.

WILLIAM BUTLER AND HENRY G. BUTLER, OF KENOSHA, WISCONSIN,
ASSIGNORS TO THE DAVY CLAY BALLAST COMPANY, OF ILLINOIS.

METHOD OF BURNING CLAY FOR BALLAST, &c.

SPECIFICATION forming part of Letters Patent No. 413,358, dated October 22, 1889.

Application filed April 1, 1889. Serial No. 305,508. (No model.)

To all whom it may concern:

Be it known that we, WILLIAM BUTLER and HENRY G. BUTLER, citizens of the United States, residing at Kenosha, in the county of 5 Kenosha and State of Wisconsin, have invented a new and useful Improvement in Methods of Burning Clay to Make Ballast, &c., of which the following is a specification.

Our invention relates particularly to an improvement in the method as set forth in Letters Patent of the United States No. 371,042, granted on the 4th day of October, 1887, to William Davy, and entitled "Method of Making Ballast and Paving Material," which method 15 is an improvement on that set forth in Letters Patent of the United States, No. 305,432, granted on the 23d day of September, 1884, also to the aforesaid William Davy, and consisting, broadly stated, in burning clay in the open 20 air to accomplish the object of the invention, instead of in kilns, as it had previously been burned.

In order that our present improvement may be the more readily understood, we state 25 briefly the aforesaid method, in which it is stated to constitute an improvement.

A location is selected, ordinarily near a railroad, upon ground containing clay, which term includes any suitable dirt. Fuel (kindling) is then laid in a line perhaps a thousand 30 or more feet in length, when clay is dug along one side of the line of fuel and a few feet therefrom, whereby a trench is formed incipiently, and the clay is heaped on the fuel 35 to a thickness of several inches. The interstices between the clay are then supplied with coal, and openings may be left at intervals near the top of the long heap, through which to introduce coal-oil, or the like readily- 40 inflammable material, where the igniting is performed, after which the openings should be supplied with coal and filled up with clay. As soon as the fire has made sufficient headway it is "slaked" with coal; and when the 45 pile has become a glowing mass another covering of clay, dug like the first, thereby deepening and widening the trench, is applied, and in due course slaked with coal before piling on another layer of clay. The piling on of 50 clay and subsequent slaking are continued

at intervals until the fire requires drawing or raking. Eventually, by the gradual increase of the width of the pile toward the trench, it reaches the latter, and is continued in the same, sloping toward it from the top of the 55 heap, and from time to time drawn or raked. The trench from which the layers of clay are applied is gradually increased in depth till it becomes about eight feet deep, after which it should be merely widened, without deepening 60 it. When the pile reaches a desired height, a shoulder is formed along the edge of its top, and from the shoulder, when its substance has become sufficiently hot, the glowing material is shoveled down upon the side of the 65 heap, filling up unevenness and giving renewed impetus to the fire.

Our improvement differs from the method thus briefly described in the following particulars, among others hereinafter to be 70 stated:

We do not lay the fire a material distance away from the trench, nor burn on opposite sides of a heap, but extend the pile immediately into the trench by replenishing it with 75 fuel and clay only on the side of the pile adjacent to the trench.

We avoid drawing or raking of the fire and undermining it to precipitate it into the trench, and thereby materially obviate cooling by the exposure of the glowing mass, and we secure the same avoidance as to the glowing shoulder by the particular manner we observe in forming and utilizing it.

Among the more important objects to be 85 accomplished by our improvement the following may be stated: To save time and labor in laying the fuel; to diminish the draft at and near the bottom of the pile, thereby to avoid intensifying the fire above the base at the 90 expense or to the detriment of the burning of the mass at the base portion thereof; to increase the area of the pile from the beginning of its formation without decreasing proportionately the desired ready accessibility 95 to it for applying the clay and fuel; to permit equally good—that is, first-class—ballast to be produced throughout, or substantially throughout, the pile; to avoid drawing or raking the fire, and consequent material open- 100

ing thereof; and to improve the burning, especially of "close or slow burning clay," as the dirt burned is termed, by a particular manner of forming and utilizing the shoulder extended from the top of the pile.

By way of assisting a ready comprehension of our improvement, we have, so far as is necessary to represent the steps practiced in carrying out our method, illustrated them 10 in the accompanying drawings, in which—

Figure 1 represents a cross-sectional view of the fire, including in the term the pile and its immediate surroundings, in an incipient stage. Figs. 2 and 3 represent similar views 15 of the same, respectively illustrating more advanced stages; and Fig. 4 is a similar view thereof at a still more advanced stage.

To start a new "fire," or, in other words, commence a new "burning," we dig (by 20 hand or (and preferably) by suitable machinery we employ for the purpose) a trench, and pile the earth at one side of the trench in a manner to cause it to slope from its top toward the trench at the side of the latter on 25 which it is piled, thus forming a long pile *r*, slanting on both sides, and extending the length of the trench, which thus corresponds in length with that of the fire. Upon the sloping side of the pile *r*, (which we suggestively term the "spoil-bank,") nearest the trench, we place any suitable fuel for kindling, preferably wood, and upon the latter we apply additional fuel, coal being preferred. A layer of earth dug from the trench 35 is then piled on the prepared side of the spoil-bank, during which operation care should be taken to provide at intervals openings at which to introduce fire for igniting the fuel. After ignition the openings provided, as aforesaid, for the purpose should 40 be filled with earth, thereby to complete the covering. When the fire has made sufficient headway, additional fuel is applied to the surface of the burning pile, or the fire is again 45 slackened with coal previous to imposing another layer of the clay, and thenceforward the alternate slaking and piling on of clay are proceeded with, as described in the said Patent No. 371,042.

The advantages of the above-described proceeding of forming the spoil-bank are that by forming the trench and placing the soil taken from it close to the excavation room is attained for building the fire both low and 55 high at the start, thereby initially providing a large continuous surface for the burning and permitting the trench to be deepened rapidly, thereby permitting early access to the better quality of dirt for burning; and by 60 providing a solid bank *r* much time is saved over the former method referred to in placing kindling; and as a primary advantage the spoil-bank, by partly closing the base of the pile, prevents the draft or cold wind striking 65 it from driving out the heat, whereby the heat by being retained increases and is forced to the surface the more rapidly, and as the

pile increases in dimensions the heat is prevented from becoming intense above the base to the detriment of that at the bottom, between the base of the trench and apex of the spoil-bank.

When the pile or fire has been increased to such dimensions and burned sufficiently long to afford its own protection—that is, when 70 the mass between the bank *r* and trench has been burned and cooled to a sufficient thickness to afford the desired protection—the spoil-bank may be gradually removed and carried over to the opposite side or "breast" 75 of the pile and burned, thereby cleaning it up and having only first-class ballast throughout the pile. As will hereinafter be explained, however, the spoil-bank, or at least a portion of it, is utilized for a further purpose than 80 of that described before being spread over the breast of the fire.

Should there, from time to time during the burning, be any unburned dirt on the pile, as there may be at different points, instead of 85 opening and drawing the fire, as is practiced according to the aforesaid Patent No. 371,042, the unburned dirt is removed by shoveling it to one side, and on the ground (in the trench) close to the base of the fire, fuel (preferably coal) is scattered, and red-hot substance 90 is shoveled thereon from the breast of the fire from a distance of several feet above the bottom, care being taken to avoid opening the fire so much as would permit material exposure of the glowing mass; and upon this scattered foundation of fuel and hot clay additional fuel is applied, and the previously-removed unburned portions are imposed upon 95 it. When the long pile has reached a height 100 (say five feet from the surface of the ground) beyond which it is not deemed practicable to continue it, and after which it is only increased in width and in depth in the trench, we build, especially for close or slow burning 105 dirt, a shoulder *p*, by raising it from the finished or leveled top of the pile to a height of 110 from six inches to one and one-half foot, (more or less,) more particularly for the purpose of covering the material forming the finished 115 top, and thereby allowing it to be thoroughly 120 burned. The shoulder is maintained several feet (about two or three) wide, and is so maintained by shoveling, each time the breast of the fire (including that of the shoulder) is 125 covered with a layer of clay to be burned, so much from the rear side of the shoulder upon the breast of the fire as will equal or about equal the fresh covering of clay, thereby utilizing it as fuel and affording proportionate 130 saving in the latter, besides the advantage of the heat it contains. As the back of the shoulder is removed in the manner and for the purpose described, we bank it up to protect it against exposure by shoveling dirt from 135 the spoil-bank and poor material and dirt thrown over in covering the face, thereby also "cleaning up" as we proceed; and the dirt thus placed at the back of the shoulder in

each covering thereof is shoveled over upon the breast of the fire before a succeeding layer of clay is applied thereto, thus procuring the burning of all the mud or dirt and producing 5 clean hard-burned ballast throughout the pile.

We employ coal for the step known as "slaking," as being, ordinarily, the preferred and most readily obtainable fuel for our purpose; but we do not wish to be understood as 10 limiting our improved method to the use of any particular kind of fuel.

What we claim as new, and desire to secure by Letters Patent, is—

1. In burning clay to produce ballast and 15 the like by forming a trench and burning adjacent to it, in the open air, material taken therefrom, the method of facilitating the burning, which consists in forming a spoil-bank *r* adjacent to the trench and construct-

20 ing the pile of fuel and clay to be burned on the side of the spoil-bank adjacent to the trench, substantially as and for the purpose set forth.

2. In burning clay to produce ballast and 25 the like by forming a trench and burning adjacent to it, in the open air, material taken therefrom, the method of facilitating the burning, which consists in forming a spoil-bank *r* adjacent to the trench, constructing 30 the pile of fuel and clay to be burned on the side of the spoil-bank adjacent to the trench, and securing the burning of any insufficiently-burned material in the pile by removing it therefrom, imposing near the base of the pile 35 fuel and burning material from the breast of the pile, and applying thereon such insuffi-

ciently-burned material, substantially as described.

3. In burning clay to produce ballast and the like by forming a trench and burning adjacent to it, in the open air, material taken therefrom, the method of facilitating the burning, which consists in forming a spoil-bank *r* adjacent to the trench, constructing the pile of fuel and clay to be burned on the side of the spoil-bank adjacent to the trench, forming on the top of the pile a shoulder *p*, spreading burning substance from the rear of the shoulder upon the breast of the pile, and covering the rear of the shoulder from which the said burning substance is taken, substantially as and for the purpose set forth.

4. In burning clay to produce ballast and the like by forming a trench and burning adjacent to it, in the open air, material taken therefrom, the method of facilitating the burning, which consists in forming a spoil-bank *r* adjacent to the trench, constructing the pile of fuel and clay to be burned on the side of the spoil-bank adjacent to the trench, 60 forming on the top of the pile a shoulder *p*, spreading at intervals burning substance from the shoulder upon the breast of the pile, and banking material from the spoil-bank against the said shoulder when the said burning substance is removed therefrom, substantially as and for the purpose set forth.

WILLIAM BUTLER.
HENRY G. BUTLER.
